UNITED STATES PATENT OFFICE.

MARGARET MILNE, OF BROOKLYN, NEW YORK.

BOUQUET-FASTENING.

SPECIFICATION forming part of Letters Patent No. 325,853, dated September 8, 1885.

Application filed April 24, 1885. (No model.)

To all whom it may concern:

Be it known that I, MARGARET MILNE, a citizen of the Kingdom of Great Britain, and a resident of the city of Brooklyn, in the county 5 of Kings and State of New York, have invented a new and useful Improvement in Bouquet-Fastenings, of which the following is a specification.

This invention relates to a new article of manufacture in bouquet-fasteners consisting of a pin having a lateral bent arm with an eye on one end and a point on the other, and to the eye loosely attached a spiral wire spring-band, so that any of the coils of the free end 15 of this band may be made to engage the point of the pin and hold more or less bouquet-flowers, as will be hereinafter fully understood.

Heretofore bouquet - fastenings have been made liable to break the stems of the flowers, 20 liable to slip the flower, and become detached from the wearer's clothing during walking, and on account of shrinkage of the stems of the bouquet. Such fastenings are also inconvenient for hasty application.

The object of this invention is to have a superior, convenient, and more positive fastening; and it consists of an elastic clamp fastening having a number of clamping spaces, so that by this means to clamp and hold the 30 stems more severely and thereby provide for shrinkage and hold the bouquet more positively to the wearer's clothing, especially during walking.

In the annexed drawings, Figure 1 represents a side view of the fastening detached, and 35 Fig. 2 a similar view of the same as applied with the bouquet according to my invention.

A represents a suitable pin with an eye, B, and a point, C, on its opposite ends. Said 40 point passes readily through the wearer's

clothing, and in said eye B is attached by an eye the end of a spiral wire spring-band, D, of which the loose end is secured by passing one of its coils over the point C after placing it over the stems of the bouquet-flowers whenever the fastening is applied. The pin A is passed laterally through the clothing at the location for the bouquet, allowing the point C to project outside. The stems of the flowers are placed across the pin A upon the clothing, 50 and the spring-band D is drawn over the stems, and its loose end with one of its coils is passed over the point C so as to hook fast the stems. By this means the coils of the wire spring press and arrange themselves between the 55 stems of the flowers of the bouquet, and not only clamp the whole of the bouquet-stems, but severally, and hold them, and clamp the same, and nearly each, in vertical, in lateral, and in longitudinal direction.

Having fully described the construction and use of my newly-invented bouquet-fastening, what I claim as my invention, and desire to secure by Letters Patent, is—

As an article of manufacture, a bouquet- 65 fastener consisting of a pin, A, having a point, C, at one end and a right-angled arm with an eye, B, at the other, and a spiral wire spring-band, D, loosely attached to said eye at one end, whereby any of the coils of the free end 70 may be made to engage the point of the pin, substantially as described.

In testimony that I claim the foregoing as my invention I have signed my name in the presence of two witnesses.

MARGARET MILNE. [L. S.]
